UNITED STATES PATENT OFFICE.

ROBERT BLACK, OF SCARSDALE, NEW YORK, ASSIGNOR TO THE DRESSEL RAILWAY
LAMP WORKS, A CORPORATION OF NEW YORK.

FOCUSING DEVICE FOR ELECTRIC HEADLIGHTS.

1,260,998.

Specification of Letters Patent. Patented Mar. 26, 1918.

Application filed March 6, 1917. Serial No. 152,763.

To all whom it may concern:

Be it known that I, ROBERT BLACK, a citizen of the United States, residing at Scarsdale, Westchester county, in the State of New York, have invented certain new and useful Improvements in Focusing Devices for Electric Headlights, of which the following is a full, clear, and exact specification.

10 This invention relates to improvements in focusing devices for electric headlights and the like, and has for its object to provide means whereby the source of light may be accurately positioned at the focal point of

15 the reflector. Further the invention has for its object to provide a device of this character in which the correct positioning of the source of light may be conveniently and easily ac-
20 complished.

Further the invention has for its object to provide a device of this character in which the source of light is held firmly in its adjusted position.

25 Further the invention has for its object to provide a device of this character comprising a casing, lamp supporting means adjustably supported thereon, and means for locking the lamp supporting means in
30 its adjusted position.

Other objects will in part be obvious and in part be pointed out hereinafter.

To the attainment of the aforesaid objects and ends, my invention consists in the novel details of construction, and in the combination, connection and arrangement of parts hereinafter more fully described and then pointed out in the claims.

In the accompanying drawings showing
40 an illustrative embodiment of the invention,

Figure 1 is a side view of a headlight embodying the invention, the side door being removed in order to expose the interior
45 thereof;

Fig. 2 is a side view of the focusing device;

Fig. 3 is a longitudinal sectional view thereof;

50 Fig. 4 is an elevational view of the locking member, and

Fig. 5 is a sectional view taken on the line 5—5 of Fig. 4.

For purposes of illustration the invention is shown in connection with the head-

light of a locomotive, but it is of course to be understood that the same may be used in connection with other types of lanterns without in any way departing from the spirit of the invention. Experience has shown that owing to irregularities in the shape and size of the lamp filament and in the securing of the lamp bulb to its base, the lamp, when mounted in a lamp socket fixed with respect to the reflector, will not always be at the exact focal point thereof. As a slight variation of the lamp from its proper position at the focal point of the reflector means a marked decrease in the amount of reflected light, it is evident that lanterns, in which the lamp socket is fixed with respect to the reflector, will in many instances be operating below their maximum efficiency. This disadvantage is overcome by means of my improved focusing device which permits the lamp to be adjusted with respect to the reflector so as to be positioned at the exact focal point thereof, thereby insuring that the lantern will at all times be operating at its maximum efficiency.

Referring to the drawings 10 designates a lantern casing of any suitable type within which is supported a reflector 11 having an opening in its rear wall. Extending rearwardly from the back of the reflector 11 and registering with the opening therein is a hollow casing 12 supported upon a bracket 13 having one of its ends secured to the lantern casing 10 and its other end embracing the casing 12 and clamped between the flanged forward end 14 thereof and a nut 15 threaded upon the casing.

Adjustably supported by the casing 12 is a tubular member 16 having secured to its inner or forward end an electric lamp socket 17 carrying an electric lamp 18 which projects through the opening in the rear wall of the reflector 11.

The rear portion of the casing 12 is provided with an exterior thread 19 with which a nut 20 is adapted to engage. The rear end of the casing 12 and the nut 20 are provided with registering curved seats 21 and 22 which, when the nut 20 is in its operative position, engage the curved peripheral surface of a split locking-ring 23 surrounding the tubular member 16 to hold the locking-ring 23 firmly in engagement with the tubular member 16 to prevent movement.

thereof. The locking-ring 23 is preferably provided with a recess or notch 24 to increase its resiliency. A plurality of adjustable thumb-screws 25 having threaded engagement with the casing 12 are adapted to have their inner ends engage the forward end of the tubular member 16 and are held in their adjusted position by lock-nuts 26.

Electrical conductors 27 connected to the terminals of the socket 17 extend through the tubular member 16 and have their other ends connected to suitable binding posts 28 carried by the bracket 13, to which binding posts are connected conductors 29 leading from a suitable source of electric current supply.

The operation of the device is as follows:—

If it is desired to properly adjust the lamp 18 with respect to the reflector 11, the nut 20 and the thumb screws 25 are first unscrewed to cause them to be moved from their operative positions. The unscrewing of the nut 20 allows the locking ring 23 to expand sufficiently to permit longitudinal movement of the tubular member 16 and the lamp 18 with respect to the casing 12. The unscrewing of the thumb-screws 25 frees them from engagement with the forward end of the tubular member 16, whereupon the locking ring 23 may be tilted upon its curved seats 21, 22 to permit the forward end of the tubular member 16 and the lamp 18 to be adjusted laterally of the casing 12. After the nut 20 and thumb-screws 25 have been unscrewed the tubular member 16 is so adjusted, by longitudinal movement or tilting movement or by a combination of both movements, as to position the filament of the lamp 18 at the exact focal point of the reflector 11. Thereupon, the thumb screws 25 are screwed into engagement with the tubular member 16, and the nut 20 is screwed into its operative position to force the locking-ring 23 to contract and tightly engage the tubular member 16, which will then be firmly held in its adjusted position.

Having thus described my invention, what I claim and desire to secure by Letters Patent is:

1. In a device of the character described, the combination with a reflector having an opening in its wall, of an electric lamp projecting through said opening and adjustably supported with respect to said reflector, means for locking said lamp in its adjusted position, and means for retaining said lamp in its adjusted position during the actuation of said locking means, substantially as specified.

2. In a device of the character described, the combination with a reflector having an opening in its wall, of a supporting member at the rear of said reflector and adjacent to the opening therein, an electric lamp ad-

justably mounted upon said supporting member and projecting through said opening, means for locking said lamp against movement relative to said supporting member, and means for retaining said lamp in its adjusted position during the actuation of said locking means, substantially as specified.

3. In a device of the character described, the combination with a reflector having an opening in its wall, of a supporting member at the rear of said reflector and adjacent to the opening therein, an electric lamp adjustably mounted upon said supporting member and projecting through said opening, means for locking said lamp against movement relative to said supporting member, and means carried by said supporting member for retaining said lamp in its adjusted position during the actuation of said locking means, substantially as specified.

4. In a device of the character described, the combination with a reflector having an opening in its wall, of a supporting member at the rear of said reflector, and adjacent the opening therein, a member adjustably carried by said supporting member, a lamp carried by said adjustable member and projecting through said opening, means for locking said adjustable member against movement relative to said supporting member, and means for retaining said adjustable member in its adjusted position during the actuation of said locking means, substantially as specified.

5. In a device of the character described, the combination with a reflector having an opening in its wall, of a supporting member at the rear of said reflector and adjacent the opening therein, a member adjustably carried by said supporting member, a lamp carried by said adjustable member and projecting through said opening, means for locking said adjustable member against movement relative to said supporting member, and means carried by said supporting member and adapted to engage said adjustable member for retaining the latter in its adjusted position during the actuation of said locking means, substantially as specified.

6. In a device of the character described, the combination with a reflector having an opening in its wall, of a supporting member at the rear of said reflector and adjacent the opening therein, a member adjustably carried by said supporting member, a lamp carried by said adjustable member and projecting through said opening, means for locking said adjustable member against movement relative to said supporting member, and thumb screws carried by said supporting member and adapted to engage said adjustable member for retaining the latter in its adjusted position during the actuation

of said locking means, substantially as specified.

7. In a device of the character described, the combination with a reflector having an opening in its wall, of a supporting member at the rear of said reflector and adjacent the opening therein, a member adjustably carried by said supporting member, a lamp carried by said adjustable member and projecting through said opening, a locking member movable into and out of engagement with said adjustable member, means for controlling the movement of said locking member, and means for retaining said adjustable member in its adjusted position during the actuation of said controlling means, substantially as specified.

8. In a device of the character described, the combination with a reflector having an opening in its wall, of a supporting member at the rear of said reflector and adjacent the opening therein, lamp supporting means adjustably carried by said supporting member, a lamp carried by said means and projecting through said opening, a resilient locking member movable into and out of locking engagement with said lamp supporting means, and means for controlling the movement of said locking member, substantially as specified.

9. In a device of the character described, the combination with a reflector having an opening in its wall, of a supporting member at the rear of said reflector and adjacent said opening, lamp supporting means adjustably carried by said supporting member,

a lamp carried by said means and projecting through said opening, a resilient split-ring surrounding said lamp supporting means and movable into and out of locking engagement therewith, and means for controlling the movement of said split-ring, substantially as specified.

10. In a device of the character described, the combination with a reflector having an opening in its wall, of a hollow casing at the rear of said reflector and having its front end registering with said opening, said casing being provided with a curved seat, a member movably supported upon said casing and provided with a curved seat registering with the curved seat of said casing when said member is in its operative position, lamp supporting means adjustably supported by said casing, a lamp carried by said means and projecting through said opening, and a resilient locking member adapted to be engaged by said curved seats and forced into engagement with said lamp supporting means when said movable member is in its operative position whereby to lock said supporting means against movement relative to said casing, substantially as specified.

Signed at the city of New York, in the county and State of New York, this 15th day of January, one thousand nine hundred and seventeen.

ROBT. BLACK.
